ABSTRACT OF THE DISCLOSURE

A process for obtaining diethylbenzene from ethylbenzene which results from the catalytic reforming of gasolines. The ethylbenzene is disproportionated in the presence of a catalytic complex based on aluminum chloride and polyalkylbenzenes in the amount of 3-10% relative to ethylbenzene, at a temperature of 80-100° C. in the absence of hydrogen. There is obtained a mixture of diethylbenzene, benzene, and ethylbenzene containing at most 1.5% of ortho-diethylbenzene and at most 2.9% of polyalkylbenzenes.

CROSS REFERENCE TO RELATED APPLICATIONS

This application is a continuation-in-part of application Ser. No. 871,594, filed Nov. 6, 1969, and now abandoned which is in turn a streamlined continuation of application Ser. No. 633,713, filed Apr. 26, 1967 and now abandoned.

BACKGROUND OF THE INVENTION

Field of the invention

The present invention relates to a process for obtaining diethylbenzene from ethylbenzene resulting from the catalytic reforming of gasoline.

Prior art

In the prior art in this field, various processes for obtaining diethylbenzene are known among which can be mentioned a process for the alkylation of benzene with ethylene in the presence of aluminum chloride or a process for alkylation of ethylbenzene with ethylene. The first of the above mentioned processes presents the disadvantage of obtaining low diethylbenzene output since the latter is obtained in the form of a secondary product of the process for obtaining ethylbenzene together with other polyethylbenzenes. The second mentioned process overcomes the disadvantages of the first by obtaining diethylbenzene as the main reaction product, its output being high. But both processes have the disadvantage of their laborious technology involving a step for obtaining ethylene by dehydration of ethyl alcohol or by pyrolysis of refinery gases followed by alkylation in the presence of aluminum chloride and also involving locating the installation for producing diethylbenzene near a source of ethylene.

Also known is a process (U.S. Patent No. 2,739,993) for the conversion of toluene to other aromatic hydrocarbons and to naphthalenes wherein toluene, in the presence of a great excess of hydrogen is subjected, in the liquid phase at a temperature of 50-300° C. to the action of 0.1 to 10 moles of aluminum chloride per mole of toluene. Characteristic of this process is the fact that there is always obtained thereby one or more compounds having a lesser number of carbon atoms than the starting toluene.

2

SUMMARY OF THE INVENTION

According to the present invention, ethylbenzene, together with 3-10%, preferably about 5% by weight of a catalyst which is $AlCl_3$ are introduced to a reaction zone in the absence of any hydrogen and reacted at a temperature of 80-100° C. at atmospheric pressure. The optimum results are obtained in about 5 minutes when the temperature is 100° C.

When compared with the process disclosed in U.S. Patent No. 2,739,993 it is seen that the present invention specifically excludes hydrogen while the known process specifically requires same. Additionally, in the present invention a much smaller amount of catalyst is used than in the known process. In the known process, 0.1 to 10 moles of $AlCl_3$ are used per mole of toluene. This is the equivalent of about 14.5-1450%; while in the present invention, only 3-10% of $AlCl_3$ is used.

DETAILED DESCRIPTION

20 The present invention overcomes the disadvantages of the known processes in that diethylbenzene (as raw material for obtaining divinylbenzene) is obtained by disproportionation of ethylbenzene obtained from catalytic reforming in the presence of a catalytic complex based on aluminum chloride in the amount of 3-10% relative to ethylbenzene, preferably 5%, at a temperature of 80-100° C. in the absence of hydrogen which leads to a conversion of 33% by weight of ethylbenzene to diethylbenzene, the final yield being 70% by weight relative to 25 the ethylbenzene introduced into the reaction. The diethylbenzene obtained by disproportionation contains a maximum of 1.5% of the ortho-isomer and thus this process is more advantageous than the above mentioned process which yields a higher proportion of o-diethylbenzene, and by dehydrogenation of the latter there is obtained naphthalene.

An example of the application of the invention is presented as follows: 1000 g. of ethylbenzene of 98% minimum purity obtained by catalytic reforming of gasolines 40 and 50 g. of $AlCl_3$ are introduced into an alkylation reactor constructed of Bakelized steel. The reactor is heated to 100° C. and intimate contact between ethylbenzene and the catalyst is provided by intensive stirring.

After about 5 minutes, an optimum diethylbenzene concentration in the reaction mass is established, this reaction mass consisting of: 22% by weight benzene, 41% by weight ethylbenzene, 33% by weight meta+para-diethylbenzene, 1.5% by weight ortho-diethylbenzene, 2.5% by weight polyethylbenzene. After washing, neutralizing, drying and fractionating the reaction product, 50 meta+para-diethylbenzene of purity over 99% are obtained, the final output being 70% for a conversion of 33% by weight relative to ethylbenzene. In order to increase the diethylbenzene output, for the further operation together with the unreacted ethylbenzene, the obtained polyethylbenzenes are also recycled. The benzene recovered in a pure state, due to the great difference of the boiling points, is obtained by a light rectification and can be used for other purposes.

60 The process according to the invention presents the following advantages:

The technique for obtaining diethylbenzene is simplified as the step of obtaining ethylene is not necessary;

A more simple apparatus is required;

65 It allows the preparation of diethylbenzene with a final output of 70% and a conversion of 33% ethylbenzene to diethylbenzene;

The obtained diethylbenzene is a mixture of the meta- and para-isomer containing a maximum of 1.5% of the ortho-isomer.

70 Concerning the fact that in U.S. Pat. No. 2,739,993 a tremendous excess of hydrogen is required, while in

the present case hydrogen is excluded from the reaction system it is considered that in the known process toluene is converted into methylcyclohexane (first stage), which then, in the presence of Friedel-Crafts type catalyst, by a series of disproportioning and redistribution reactions of hydrogen, leads to the formation of xylenes with yields of the order of 11%. Because a complex mixture of hydrocarbons having 48% heavy hydrocarbons results from the reaction in the reference, this cannot be considered as a true disproportionation reaction.

If the present invention were to be performed in the presence of hydrogen, one can suppose that the use of hydrogen would decrease substantially the process selectivity on the basis of naphthalene formation the composition of which would likely be similar to that given by Ciapette (Catalysis vol. 6, Reinhold Publ. Corp. N.Y. 1958, p. 495-687), namely:

products which appear by the opening of the ring and polymerization thereby obtaining higher paraffin hydrocarbons, probably in a higher proportion than toluene.

What is claimed is:

1. A process for preparing a mixture of diethylbenzenes substantially free of the o-isomer from ethylbenzene,

said process comprising disproportionating ethylbenzene in the absence of hydrogen and in the presence of 3 to 10% of $AlCl_3$ based on ethylbenzene at a temperature of 80-100° C. to form a mixture of diethylbenzenes substantially free of the o-isomer.

2. A process according to claim 1 wherein 5% of $AlCl_3$ is utilized.

3. A process according to claim 1 wherein the mixture is diethylbenzenes containing a maximum of 1.5% of the o-isomer.

4. A process according to claim 1 further comprising the steps of washing, neutralizing, drying and fractionating the mixture.

5. A process according to claim 1 wherein the disproportionating is effected for about 5 minutes at 100° C.

6. A process according to claim 1 wherein the mixture comprises polyethylbenzenes and further comprising recycling the polyethylbenzenes and unreacted ethylbenzene.
